Primary Examiner — Leanne Was-Englehart*Assistant Examiner* — Yelizaveta Y Masalimova(74) *Attorney, Agent, or Firm* — Kristin D. Wheeler(57) **CLAIM**

The ornamental design for a golf shoe upper, as shown and described.

DESCRIPTION

FIG. 1 is a top perspective view of a first embodiment of a golf shoe upper, showing our new design;

FIG. 2 is a lateral side elevation view thereof;

FIG. 3 is a medial side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a top perspective view of a second embodiment of a golf shoe upper, showing our new design;

FIG. 9 is a lateral side elevation view;

FIG. 10 is a medial side elevation view therof;

FIG. 11 is a top plan view thereof;

FIG. 12 is a bottom plan view thereof;

FIG. 13 is a front elevation view thereof; and,

FIG. 14 is a rear elevation view thereof.

In FIGS. 1-14, the broken lines on the top surface of the shoe form no part of the claimed design. Also, the broken lines showing a shoe outsole including logo and traction members on the bottom surface of the shoe form no part of the claimed design.
